ABSTRACT OF THE DISCLOSURE

A device is provided, which may be disposed above or below web-carrying rolls and other rotatable elements of machines, particularly with regard to filamentary tow processing machinery. The device is operative by means of material (tow) build-up, for example, on rolls, beyond a predetermined clearance which will effect a knock-off or shut-down of the machine by mechanically pivoting components of this invention, which are operative to open a mercury switch, thereby discontinuing power to the machine.

Background of the invention

In the past, various machines, particularly in machines adapted for processing filamentary tow, such as turbo staplers, or machines which receive a tow filamentary material, have been operative to pass the same through an inlet section comprising various guide bars, through tensioning rolls, through cascading roll sections, through a heating section, between intermediate pressure-applying rolls, through a section of breaker bars, through delivery rolls and through a crimper box. It has been recognized that, due to build-up of the tow, for example, on a given roll, the continuous rotation of such rolls transmits forces attendant to such build-up to roll bearings and the like, thereby subjecting bearings and other machine components to extremely high forces which tend toward breakage of machine components.

Also, in the past, many such operations have been inefficient in that considerable down time would be required during instances of tow breakage because the broken tow would often wind around various components before the machine could be shut down, thereby increasing stresses on such components to the extent that breakage and part failure would occur. In order to correct such breakage and part failure, the down time would be considerably longer than if it were only necessary to re-thread the tow web through the machine.

Summary of the invention

The present invention seeks to obviate the above and other undesirable difficulties experienced in the tow handling and processing art, as well as in other arts, by providing a novel device which may be attached to a tow handling or processing machine in preferably several places, to sense tow material build-up and to effect a knock-off or shut-down of the machine immediately. In this regard, a shaft is provided having a pivotally mounted sleeve attached thereto which carries a flap which may be engaged by tow build-up for pivoting the sleeve for actuating a mercury switch, which would then open and shut off power supply to the machine.

Accordingly, it is the primary object of this invention to provide a novel device for effecting rapid machine shut-down, comprising a shaft about which a pivotal sleeve is mounted, wherein the sleeve carries a flap, the striking of which causes pivotal movement of the sleeve and is effective to shut down the machine operation, preferably through a switching device.

2

It is another object of this invention to provide a novel device for facilitating increased machine efficiency, as well as for facilitating shut-down of the machine by an operator.

5 It is a further object of this invention to provide a novel device which may be located at several positions throughout a machine so that an operator can easily reach any such place in the event of any emergency for shutting-down the operation of the machine.

10 It is yet another object of this invention to provide a novel device for facilitating the shut-down of a machine, preferably one for carrying or otherwise processing a web of filamentary tow material, wherein a pivotal device is utilized which has a normal gravity-urged position, but which may be pivoted to another position by web or tow build-up, for shutting down the machine.

15 Other objects and advantages of the present invention will become readily apparent to those skilled in the art from a reading of the following brief description of the drawing figures, a detailed description of the preferred embodiment, and the appended claims.

20 In the drawings:
25 FIGURE 1 is a schematic side elevational view of a tow processing machine, utilizing several of the devices of this invention.

FIGURE 2 is an enlarged fragmentary transverse sectional view through the machine of FIGURE 1, taken generally along the line of II—II of FIGURE 1.

30 FIGURE 3 is an enlarged fragmentary transverse sectional view of the device illustrated in FIGURE 2 taken generally along the line of III—III of FIGURE 2, and wherein the normal position of a pivotal portion of the device of this invention is illustrated in full lines, and wherein a pivoted position of the device is illustrated in phantom lines, with a roll to which the device is applied being also illustrated in phantom lines.

35 FIGURE 4 is a top perspective view of a device according to this invention, wherein portions of the pivotal sleeve are illustrated as broken away to show several of the internal components of the device.

40 Referring now to the drawings in detail, reference is first made to FIGURE 1, wherein there is illustrated a tow processing machine, generally designated by the numeral 10.

45 Filamentary tow yarn 11 is delivered from a tow carton 12, passing through a series of curved bar guides 13, 14 and 15, over a straight bar guide 16, around a straight bar guide 17, and downward into an inlet section of the machine 10, passing around a pair of tensioning guides, 18 and 20 as illustrated in FIGURE 1, around a width control bar 21, over a tensioning guide 22, around a centering control bar 23, over a tensioning guide 24, and through the nip between a pair of input rolls, 25 and 26. The input section is generally designated by the numeral 27, and extends from the tensioning guide roll 18 to the input rolls 25 and 26. The input rolls 25 and 26 may be provided with a pressure-applying and adjusting means (not shown).

50 55 60 It will be noted that a machine shut-down device 28 of this invention is carried on atop surface portion 30 of the machine 10 and disposed generally parallel to and vertically above the axis of rotation of the roll 25.

65 The tow 11, upon passing through the input rolls 25 and 26, would pass around a plurality of cascade rolls 31, 32, 33 and 34, between a pair of plates 35 and 36 of a heater 37, around another plurality of cascade rolls 38, 40, 41 and 42, and then through a pair of intermediate rolls 43 and 44. It will be noted that the intermediate roll 44 may also be provided with a pressure-applying and adjusting means if desired, but is however,

provided with a machine shut-down device 45, also mounted on the machine surface 30.

The yarn or tow 11 then passes through an intermediate guide 46, between a pair of breaker bars 47 and 48, each of which are provided with alsimag breaking blades (unnumbered).

A pair of machine shut-down devices 50 and 51 may be provided, preferably one for each said breaker bar 47 or 48, respectively, to prevent the build-up of tow on either of such bars, thereby protecting the blades of the breaker bars 47 and 48. The device 50 may be mounted on a surface 52 of the machine 10, and the device 51 may be mounted on the side 53, as illustrated in FIGURE 1.

The tow 11 then passes through the nip provided by a pair of delivery rolls 54 and 55, either of which may be provided with pressure-applying or pressure-adjusting means (not shown). An additional machine shut-down device 56 is provided, also preferably mounted above the roll 54, yet to be described.

Upon leaving the delivery rolls, the yarn or tow 11 then passes over a guide bar 57, between a pair of reducing guides 58, through a guide tray 60, to be delivered to a crimper feed device 61 between a pair of crimped rolls 62 and 63 to a crimper box 64, from which the crimped yarn 65 may then pass into a sliver can 66, for subsequent delivery to a material fabricator, or the like.

It will be noted that each of the devices 28, 45, 50, 51 and 56 is substantially the same, differing only in mounting. It will further be apparent that additional such devices may be utilized, for example, mounted below the rolls 26, 43, and 55, if desired. Each of the devices 28, 45, 50, 51 and 56 is substantially identical in construction, and, therefore, only the device 28 need be described in detail.

With particular reference FIGURE 2, it is seen that the machine shut-down device 28 comprises a fixed shaft 67, having a block 68 on one end, the block 68 being slidably carried within a vertical slot of a block 70, and being locked in a given position therein by means of a cap-headed screw 71, secured within a tapped hole 69 of the block 68, through a slotted hole 72. The block 70 has a base flange 73 which is welded or otherwise secured to the upper surface 30 of the machine supporting structure 29, as shown in FIGURE 2.

At two places along the fixed shaft 67, there are provided a pair of anti-friction bearings 74 and 75, each having an inner race 76, press-fitted or otherwise secured to the shaft 67, and an outer race 77 welded, soldered or otherwise secured to a right-circular cylindrical sleeve 78 disposed about the shaft 67. Between each of the races 76 and 77 of each of the anti-friction bearings 74 and 75, there are provided rolling elements (not shown) or the like. The anti-friction bearings 74 and 75 are secured to the shaft 67 by suitable retainers 80, for assuring the positions of the inner races 76 of the bearings 74 and 75 along the shaft 67.

The sleeve 78 may have closed ends 81 and 82, to prevent damage to components therein, and to prevent accidental accumulation of tow therein, if desired.

A weight 83, for example of key stock or the like is provided inside the sleeve 78, being welded or otherwise secured to the outer races 77 of each of the bearings 74 and 75, to pivot beneath the shaft 67 with the sleeve 78. The weight 83 is operative by means of gravity to allow 67, but, with the axes of the shaft 67 and sleeve 78 with the sleeve 78 eccentrically disposed about the shaft 67, but, with the axes of the shaft 67 and sleeve 78 parallel but spaced from one another, and aligned in a common substantially vertical plane, to assure a pivotal movement of the sleeve 78 in a manner such as that shown in FIGURE 3, between the full line and phantom positions of the sleeve 78 illustrated therein. A bracket 84 is secured by means of bolts or the like to one end of the weight 83 and carries a mercury switch 85 thereon,

the mercury switch 85 being connected into a power circuit which drives the machine 10 by means of wire leads 86 and 87 which pass through clearance holes 88 and 90 in one end 81 of the sleeve 78.

A flap 91 of rubber or like construction, is carried by the body 79 of the sleeve 78 by means of brackets 92 and 93. The flap 91 is generally stiff, but would be sufficiently resilient not to be damaged by tow striking an edge thereof. It will be noted that the flap 91 is disposed above the roll 25, to provide a running clearance there-between indicated at 94 to be approximately $\frac{1}{16}$ of an inch, but which may be adjusted as desired by means of the screw 71 and slot 72 to any desired clearance.

With particular reference to FIGURE 3, it is seen, that the device 28 would be operative such that, as the roll 25 rotates in a counter-clockwise direction as illustrated in FIGURE 3, the web or tow carried thereby would normally pass beneath the flap 91 of the device 28, through the $\frac{1}{16}$ of an inch clearance slot 94. However, should the tow 11 break or for any other reason tend to build-up on the roll 25, as soon as such enlarged portion of the tow 11 struck the lower-most edge of the flap 91, the flap 91 would be pivoted in a clockwise direction about the shaft 67, to the phantom line position illustrated in FIGURE 25 3, also causing the counter-clockwise pivoting of the sleeve 78, such that the bearing outer races 77 secured thereto, and the weight 83 secured thereto would also pivot in the same direction causing a "tilting" of the mercury switch 85, which would be operative to open the circuit which provides power to the machine 10.

All of the devices or knock-offs 28, 45, 50, 51 and 56 are operative in a similar manner, it being readily apparent that in a case of any knock-off devices which would be mounted beneath a roll, such as at 51, the flap 35 91 would be disposed on an opposite side of the sleeve 78 from the side having the weight 83 or across the pivot shaft 67 relative to the weight 83. It would further be apparent that the placement of the flap 91 precisely above the axis of rotation of a roll such as that 25, will yield the 40 most direct pivoting of the sleeve 78 in response to tow build-up on the associated roll 25.

By positioning the devices 28, 45, 50, 51 and 56, as shown in FIGURE 1, or over the three (3) main drive rolls and about the breaker bars, the machine will be protected against build-up or lap-up from damaging numerous components of the machine 10 of this invention. For example, the knock-off 28 would prevent damage to the top and bottom input rolls, as well as prevent damage to the cushion on these input rolls and any gearing and cots used as well as any tow guide used.

By positioning the device 45 where shown, damage would be prevented to the top and bottom intermediate rolls, their cushions, all their gearing and cots, and their brushes and brush holders.

The placement of the devices 50 and 51 about the breaker bars would prevent damage to all alsimag blades and to the top and bottom breaker bar shafts. The placement of the device 56 as shown would prevent damage to the top and bottom delivery rolls, their cushions, all 60 their gearing and cots, as well as their brushes and brush holders.

It is apparent that the knock-off or machine shut-down device as shown and described will protect various machine components against damage caused by stock lap-up as well as increase machine efficiency by reducing the down time which would be attendant to reduced mechanical failures, such reduction in mechanical failures being effected by the use of the devices of this invention. Also, it is to be noted that the machine shut-off device of this invention is extremely useful as a safety device, for the safety of operators or attendants of the machine 10 or any similar machine in that, by the placement of such devices throughout a machine, an operator can readily reach any single knock-off or device in the event of an emergency, and strike the same causing the pivotal move-

ment of the same to operate the mercury switch in the manner described for intentional shut-down of the machine.

While only a preferred embodiment of the device has been shown and described, and while only a preferred use of the same has also been disclosed herein, it will be apparent that various modifications may be made in the details of construction, as well as in the use of the device of this invention, all within the spirit and scope of the invention.

What is claimed is:

1. A device for facilitating rapid machine shut-down of machines conveying continuous material past moving components thereof, in response to undesirable build-up of material on machine components, said device comprising, a fixed shaft for mounting spaced from and across a machine component on which material is carried, a sleeve disposed about said fixed shaft, means permitting pivotal movement of said sleeve about said fixed shaft, flap means carried by said sleeve for disposition with an end of said flap means mounted for running clearance relative to a machine component, and means responsive to relative pivotal movement between said shaft and pivotal sleeve for effecting a discontinuance in machine operation.

2. The device of claim 1, wherein said means permitting pivotal movement comprises anti-friction bearing means.

3. The device of claim 1, wherein weighting means are provided inside said sleeve, mounted for pivotal movement with said sleeve, for urging the orientation of said

flap means in a selected direction relative to a given moving machine component.

4. The device of claim 1, wherein said latter means comprises mercury switch means.

5. The device of claim 1, wherein at least one machine component is included in the combination, said component comprising a rotatable member, said sleeve having its axis of rotation parallel to and in substantially the same vertical plane as the axis of rotation of said machine component, said flap means also being normally disposed in said same plane.

6. The device of claim 5, wherein means are provided for adjustably positioning said flap means with an end thereof in close disposition relative to said machine component.

7. The device of claim 5, wherein a plurality of roll-like members are provided in pairs, comprising said rotatable members, and wherein said pairs are provided with at least one said shut-down device.

8. The device of claim 5, wherein said rotatable member comprises a breaker bar of a filamentary-tow-handling machine.

9. The device of claim 2, wherein said sleeve is eccentrically carried relative to said shaft.
